Primary Examiner — Wan Laymon*Assistant Examiner* — Mark Booker(74) *Attorney, Agent, or Firm* — Laura L. Bozek(57) **CLAIM**

The ornamental design for a roll dispenser, as shown and described.

DESCRIPTION

This application relates to the following design application being filed concurrently herewith:

Application Ser. No. 29/545,249, entitled Roll Dispenser. The disclosure of the foregoing application is hereby incorporated into this application in its entirety by reference thereto.

FIG. 1 is a perspective view of a roll dispenser showing my new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof; and,

FIG. 7 is a bottom plan view thereof.

The portions of the roll dispenser shown in broken lines form no part of the claimed design.

1 Claim, 4 Drawing Sheets(56)
